UNITED STATES PATENT OFFICE

152,383

DESIGN FOR A HIGH CHAIR

Walter W. Waaranan, Hubbardston, Mass., assignor to Arlington Chair Co., Gardner, Mass., a corporation of Massachusetts

Application December 27, 1946, Serial No. 135,787

Term of patent 14 years

(Cl. D15—8)

To all whom it may concern:

Be it known that I, Walter W. Waaranan, a citizen of the United States, residing at Hubbardston, in the county of Worcester and State of Massachusetts, have invented a new, original, and ornamental Design for High Chair, of which the following is a specification, reference being had to the accompanying drawing, forming part thereof.

The single figure is a perspective view of a high chair, showing my new design.

I claim:

The ornamental design for a high chair, as shown.

WALTER W. WAARANAN.
